US0D1055029S

(12) **United States Design Patent** (10) **Patent No.:** **US D1,055,029 S**
(45) **Date of Patent:** **** Dec. 24, 2024**

(54) **PAIR OF WIRELESS EARPHONES**

(71) Applicant: **Jrumz Ear Wear LLC**, Harvey, LA (US)

(72) Inventors: **Lana Joseph**, Harvey, LA (US); **Jamaul Ford**, Harvey, LA (US)

(73) Assignee: **Jrumz Ear Wear LLC**, Harvey, LA (US)

(**) Term: **15 Years**

(21) Appl. No.: **29/882,162**

(22) Filed: **Jan. 11, 2023**

(51) **LOC (14) Cl.** **14-01**

(52) **U.S. Cl.**

USPC **D14/223**

(58) **Field of Classification Search**

(57) **CLAIM**

The ornamental design for a pair of wireless earphones, as shown and described.

DESCRIPTION

FIG. 1 is a perspective view of a left ear wireless earphone, of a pair of wireless earphones showing our new design, the left ear wireless earphone shown separately for ease of illustration;

FIG. 2 is a perspective view of a right ear wireless earphone, of a pair of wireless earphones thereof, the right ear wireless earphone shown separately for ease of illustration;

FIG. 3 is a rear perspective view of FIG. 1 thereof;

FIG. 4 is a front perspective view of FIG. 1 thereof;

FIG. 5 is a front elevational view of FIG. 1 thereof;

FIG. 6 is a front elevational view of FIG. 2 thereof;

FIG. 7 is a rear elevational view of FIG. 1 thereof;

FIG. 8 is a rear elevational view of FIG. 2 thereof;

FIG. 9 is a side elevational view of FIG. 1 thereof;

FIG. 10 is a side elevational view of FIG. 2 thereof;

FIG. 11 is a side elevational view of FIG. 1 thereof;

FIG. 12 is a side elevational view of FIG. 2 thereof;

FIG. 13 is a top view of FIG. 1 thereof;

FIG. 14 is a top view of FIG. 2 thereof;

FIG. 15 is a bottom view of FIG. 1 thereof; and,

FIG. 16 is a bottom view of FIG. 2 thereof.

The broken lines in the drawings depict portions of the pair of wireless earphones that form no part of the claimed design.
